UNITED STATES PATENT OFFICE.

ROBERT J. BARTHOLOMEW, OF LANSDALE, PENNSYLVANIA, ASSIGNOR TO FLETCHER WORKS, INCORPORATED, OF PHILADELPHIA, PENNSYLVANIA, A CORPORATION OF PENNSYLVANIA.

TURNBACK APPARATUS.

Application filed March 25, 1927. Serial No. 178,221.

My invention relates to an improvement in turnback apparatus, and, while capable of various applications, will be described particularly in connection with Jacquard looms, and in this connection has for one of its objects the provision of means whereby the harness mechanism may be turned back to pick up a broken thread, or for any other reason, and the weaving resumed at the right point.

A further object of the invention is the provision of means for the purpose above mentioned which is extremely simple in construction and in operation although providing the maximum accuracy, which is a very desirable feature in this type of apparatus.

A still further object of my invention is the provision of means in turnback apparatus wherein the driven member is turned back a predetermined part of a revolution at each operation, and so arranged that if the driven member is turned back less than this amount, the driven member will automatically find its proper position relative to the driving means when driven in a forward direction.

A still further object of my invention is the provision of a turnback in which the turn back is accomplished by a single movement of the operator, the driven member being positively held in predetermined relation with respect to the driving means when driven in a forward direction.

In the accompanying drawings, wherein I have illustrated an embodiment of my invention—

Fig. 1 shows the same in elevation;

Fig. 2 is a section on the line 2—2 of Fig. 1; and

Fig. 3 is a part sectional and elevational view.

Referring to the drawings in detail, 1 designates the card cylinder or driven member carried on a shaft 2 and intermittently rotated to present the successive faces of the cards to the needles 3. The shaft 2 carrying the card cylinder is attached to reciprocating mechanism, designated 4, this reciprocating mechanism moving the card cylinder and its associated mechanism back and forth from right to left, as viewed in Fig. 1, so as to bring the card cylinder into proper operative

position relatively to the needles. This construction is usual in looms, and hence will not be described in any further detail.

For the purpose of rotating the card cylinder or driven member intermittently, I provide the Geneva gear or driving means 5, mounted loosely on the shaft 2, which is given an intermittent motion by the pin 6 carried by the rotatable drive member 7, which drive member is driven through a drive chain 8. The drive member 7, I may mention, is reciprocated with the card cylinder, and for the purpose of retaining the proper tension on the drive chain due to the reciprocating movement of the drive member 7, I provide gears 9 and 10. Intermediate the Geneva gear 5 and the card cylinder is a ratchet 11, concentric with the Geneva gear 5 and integral therewith and mounted on the shaft 2.

The shaft 2 has affixed to it a cylinder drive disc 12 and intermediate the ratchet 11 and this cylinder drive disc is a ratchet wheel 13, this ratchet wheel being loosely mounted on the shaft 2.

Rigidly secured to the cylinder drive disc 12 and passing through a slot 14 in the ratchet wheel 13 is a pin 15, which pin carries a push pawl 16, this pawl being at the side of the ratchet wheel 13 opposite the cylinder drive disc 12. A spring 17 has one end attached to the push pawl 15, as indicated at 18, while its other end is attached to the face of the ratchet wheel 13, and the normal operation of this spring is to hold the pawl 16 in one of the notches 19 in the ratchet 11. The lower side of the push pawl 16 has a cam surface 20 co-operating with a pin 21, as will be pointed out hereinafter. The ratchet wheel 13 is connected to the cylinder drive disc 12 by a yielding connection 22 in the form of a coil spring, one end of this spring, as will be understood, being attached to the ratchet wheel 13 while the other end is attached to the cylinder drive disc.

The shaft 2 carries a bracket 23, which forms a support or pivotal bearing for a reversing lever 24, which lies above the card cylinder and its associated mechanism, which has just been described. The reversing lever 24 is in the form of a bell crank lever, that is to say, its fulcrum is intermediate its

ends, and one end of this lever, that is to say, the end adjacent the needles 3, is provided with a tension spring 25, while at the other end of the lever is provided an operating chain 26. Pivotally mounted on the reversing lever 24, intermediate the pivot 23 and the end of the lever to which the chain is attached, I provide a reversing pawl 27, which is held in proper position by a tension spring 28. The lower end of this reversing pawl is forked, as indicated in Fig. 3, and this fork straddles the ratchet wheel 13 when the lever 24 is depressed, as will be hereinafter pointed out. In this forked or bifurcated end of the reversing pawl 27 I provide a pin 29, this pin co-operating with the notches 30 in the edge or periphery of the ratchet wheel 13.

Although the card cylinder 1 has been shown in Fig. 1, for instance, with one edge instead of a side thereof opposed to the needles 3, it will be understood that this is due to the fact that the card cylinder and all of the mechanism associated therewith, as illustrated in Fig. 1, has not been moved to its extreme right-hand position and that when this mechanism has been moved to its extreme right-hand position, as viewed in Fig. 1, a flat face of the card cylinder will be presented to the needles so that the same may enter the cards thereon.

In its normal operation the card cylinder or driven member is driven in a clockwise direction, as viewed in Fig. 1, the driving pin 6 carried by the driving member 7 engaging the star wheel or Geneva gear 5, driving the same clockwise, and inasmuch as the ratchet 11 is integral therewith, the latter will be driven in a clockwise direction also. At this time, due to the tension of the spring 17, the push pawl 16 will be held in one of the notches in the ratchet 11, as illustrated in Fig. 1, and consequently, intermittent rotary movement will be imparted to the cylinder drive disc 12 through the pin 15, which, it will be recalled, is fastened to the drive disc. Inasmuch as the drive disc is rigidly secured to the shaft 2, the card cylinder 1 will be intermittently rotated.

Assuming that it is desired to turn back the card cylinder or driven member, it is merely necessary to depress the reversing lever 24 by pulling downwardly on the operating chain 26. This draws the reversing pawl 27 downwardly until the pin 29 carried by the forked end thereof engages one of the notches 30 in the ratchet wheel 13. The ratchet wheel 13 will thus be reversed in direction of rotation, without, however, reversing the Geneva gear 5 and its attached ratchet 11. The rearward movement of the ratchet wheel 13 will carry the pin 21 in an anti-clockwise direction, and the action of this pin on the cam face 20 of the push pawl 16 will lift this pawl out of engage-

ment with one of the notches in the ratchet 11 so that operative driving connection between the Geneva gear 5 and the card cylinder is broken. A further depression of the reversing lever 24 will continue to rotate the ratchet wheel 13 in an anti-clockwise direction until the right-hand end of the slot 14, as viewed in Fig. 1, engages the pin 15, whereupon the pin 15 will be moved anti-clockwise, carrying with it the cylinder drive disc 12, and hence the card cylinder 1. The parts are so proportioned that full depression of the reversing lever 24 will rotate the card cylinder in an anti-clockwise direction the proper or predetermined distance. If for any reason the lever 24 is not depressed for its full distance, the driven member or card cylinder will be turned back only a part of its predetermined distance, and the driven member will automatically find its proper position relative to the driving means when the driven mechanism is turned forward.

If it is desired to further reverse the card cylinder, it is merely necessary to release the operating chain 26, allowing the reversing lever 24 to return to its original position, and then again depress the same. Assuming, however, that the mechanism has been turned back the desired amount, the operating chain 26 is released, the reversing lever 24 rises or returns to the position shown in Fig. 1, and inasmuch as the spring 17 is released due to the movement upwardly of the reversing pawl 27 out of its notch in the ratchet wheel 13, this spring will draw or pull the ratchet wheel 13 in a clockwise direction until the left-hand end of the slot 14 in the ratchet wheel 13 engages the pin 15, and at the same time the push pawl 16 will drop down into one of the notches in the ratchet 11, so that the mechanism, that is to say, the card cylinder, will now be driven in a clockwise or normal direction.

From the foregoing it will be seen that I have provided an apparatus whereby the harness mechanism of a Jacquard loom may be turned back for any purpose desired, and will always resume weaving at the proper point, this being effected by the simple manipulation of the operating chain 26.

It will be apparent also that I have provided a turnback apparatus in which the driven member and driving means therefor are always in proper predetermined relative positions.

It is evident that various modifications may be made in the construction above described within the purview of this invention.

What I claim is:

1. In a turnback for looms, the combination of a card cylinder, a drive shaft carrying the same, a cylinder drive disc rigidly attached to said drive shaft, a ratchet wheel on said shaft, a spring connection between

said cylinder drive disc and said ratchet wheel, a pivoted reverse pawl adapted to effect reverse movement of said ratchet wheel thereby to effect reverse movement of the

5 cylinder drive disc and card cylinder, a pivoted lever for actuating said pawl, and means for manually moving said lever about its pivot.

2. In a turnback for looms, the combination of a card cylinder, a drive shaft carrying the same, a cylinder drive disc rigidly attached to said shaft, a ratchet wheel loosely mounted on said drive shaft, a coil spring connection between said cylinder drive disc 15 and said ratchet wheel, one end of said spring being attached to the drive disc and the other end to the ratchet wheel, a pivoted reverse pawl carrying a pin at its free end for co-operation with said ratchet 20 wheel, and a pivoted reverse lever carrying said reverse pawl, said reverse lever being manually actuated to effect engagement of the reverse pawl with the ratchet wheel thereby to reverse the ratchet wheel, cylinder drive disc and card cylinder.

3. In a turnback for looms, the combination of a card cylinder, a drive shaft carrying the same, a cylinder drive disc rigidly secured to said shaft, and gearing yieldingly attached to said drive disc for driving the latter in a forward or normal direction, and manually operable mechanism for reversing the card cylinder without reversing the said mechanism by which the card cylinder is 35 driven in a forward direction.

4. In a turn-back for looms, the combination of a card cylinder, a drive shaft carrying the same, a cylinder drive disc rigidly secured to said shaft, an intermittent gear 40 operatively connected to said drive disc for driving the card cylinder in a forward direction, and manually operated means for disconnecting the intermittent gear from operative engagement with the drive disc 45 and to reverse the direction of said drive disc without reversing the direction of rotation of the intermittent gear.

5. In a turnback for looms, the combination of a card cylinder, a drive shaft therefor, a cylinder drive disc secured to said shaft, a ratchet wheel on said shaft, a ratchet, a pin carried by said drive disc and passing through a slot in said ratchet wheel, a pawl on said pin and engageable with said ratchet, means for driving said ratchet to drive said drive disc through said pawl, a 55 reverse pawl engageable with said ratchet wheel, and manually operable means for

moving the first mentioned pawl to inoperative position and the reverse pawl to operative position to effect thereby reversal of the cylinder drive disc and cylinder.

6. In a turnback for looms, the combination of a card cylinder, a cylinder drive disc attached thereto, an intermittent gear, 60 means for rotating said gear, a ratchet movable with said gear, a pawl carried by said drive disc and co-operable with said ratchet to effect motion of the drive disc from said intermittent gear, a ratchet wheel intermediate the drive disc and said ratchet and connected to said drive disc, a reverse pawl co-operating with said ratchet wheel, and means for effecting a disengagement of the first mentioned pawl with said ratchet and 65 an engagement of the reverse pawl with the ratchet wheel to reverse the cylinder drive disc and cylinder.

7. In a turnback for looms, the combination of a card cylinder, a drive disc for the same, a drive ratchet, a reverse ratchet wheel intermediate the ratchet and drive disc, a pin carried by the drive disc and passing through said ratchet wheel, a push pawl carried by said pin and co-operating with 80 said ratchet to effect a driving connection between the ratchet, ratchet wheel and drive disc in a forward direction, a reverse pawl 85 co-operating with said ratchet wheel for disengaging the first mentioned pawl from the ratchet and reversal of direction of rotation of the ratchet wheel, drive disc and card cylinder.

8. In a turn-back for looms, the combination of a cylinder drive disc, a drive ratchet, 90 a push pawl, a pin carrying said pawl, means for driving the ratchet in a forward direction thereby to drive the drive disc through said pawl in a forward direction, a ratchet wheel intermediate the drive disc and drive ratchet having movement relative to said ratchet, said ratchet wheel being provided with a slot for receiving said pawl-carrying pin, means for moving said ratchet wheel reversely with respect to said ratchet, 95 a pin carried by said ratchet wheel and engageable with said push pawl to move the push pawl out of operative position, and means connecting the ratchet wheel and drive disc whereby upon reversal of the 100 ratchet wheel the drive disc will be reversed.

This specification signed this 17th day of February, 1927.

R. J. BARTHOLOMEW.
